SAFETY RAZOR

Filed May 21, 1931

INVENTOR

BY *JOSEPH MUROS*
T. F. Bourne
ATTORNEY

UNITED STATES PATENT OFFICE

JOSEPH MUROS, OF NEW YORK, N. Y., ASSIGNOR TO GILLETTE SAFETY RAZOR COMPANY,
OF BOSTON, MASSACHUSETTS, A CORPORATION OF DELAWARE

SAFETY RAZOR

Application filed May 21, 1931. Serial No. 538,990.

Safety razors of the class comprising blade clamping members, which include a guard member and a cap or blade backing member, are frequently provided with means to register the members in shaving relation, the same means also registering the blade in shaving position between said members, the blade customarily being provided with one or more apertures that fit the said means for registering or locating the blade in shaving position.

The object of my invention is to provide a safety razor having blade clamping members; said members having cooperative means to register them in shaving position, one of said members having additional means to locate or register a blade in shaving position between the members, which blade does not have an aperture to fit the means that register the clamping members, which blade would otherwise be loose between said members.

In carrying out my invention I provide blade clamping members and means to clamp said members against a blade, one of said members having projections adapted to cooperate with the other member to register said members in shaving position, said projections being adapted to enter a corresponding aperture or apertures in a blade to register said blade in shaving relation to said members, one of said members also having means to engage a blade that is provided with an aperture not adapted to fit said projections to register the blade in shaving position between the members.

My invention also comprises novel details of improvement that will be more fully herein-after set forth and then pointed out in the claims.

Reference is to be had to the accompanying drawing, wherein

Fig. 1 is an edge view of a safety razor embodying my invention;

Fig. 2 is a section on line 2, 2, in Fig. 1;

Fig. 3 is a section on line 3, 3, in Fig. 2;

Fig. 4 is a partly broken plan view of Fig. 1, and

Fig. 5 is an inverted plan view of the cap member.

Similar numerals indicate corresponding parts in the several views.

My improved safety razor comprises a blade clamping member including a guard member 1 and a cap or blade backing member 2. At 3 is a handle shown provided with a threaded recess 4 at one end adapted to receive a threaded stem 5 projecting from the cap 2, which stem is adapted to pass through an opening 1a in the guard member, whereby when the parts are assembled, as in Fig. 2, the members 1 and 2 will clamp a blade 6 between them. The guard member 1 is shown provided with spaced projections 7, and the cap or backing member 2 is provided, in its under surface, with recesses 8 that are adapted to receive and fit the projections 7, whereby the guard member and the cap will be located and retained in shaving relation when said members are clamped together against a blade. The projections 7 and the recesses 8 may have any desired contour. Said projections are adapted to receive an appropriately shaped opening or openings in a blade to locate said blade on the guard member and retain the blade in shaving position between the members 1 and 2.

In case a blade 6, having a large internal opening 6a, such as a longitudinal slot, that will not fit the projections 7 to register the blade in shaving position, be applied in the razor, it would not be retained in shaving position with respect to the guard and the cap. I provide one of the clamping members with means independent of the projections 7 to engage the blade 6 to retain it in shaving position between the members 1 and 2. I have illustrated a cap or blade backing member 2 as provided at its ends with projections 9 that extend beyond the ends of the guard member, when the parts are assembled as in Fig. 2, which projections are adapted to cooperate with the end portions of the blade 6 to register the same. Said blade is shown provided at its ends with projections 6' adapted to engage the projections 9 of the cap. The projections 6' are shown spaced apart to receive the projections 9 between them at corresponding ends, whereby the projections 6' are formed, the projections 9

being adapted to enter the recesses 6" when the parts are assembled, (Fig. 4). The projections 6' are shown located beyond the cutting edges at the ends of the blades.

5 When the parts are to be assembled for shaving, the cap or blade backing member 2 may be placed in the inverted position shown in Fig. 5. The blade may be placed upon the cap with the projections 9 entering the recesses 6" of the cap to locate the blade in shaving relation to the cap, and the guard member may be placed upon the blade, the projections 7 of the guard member passing through the relatively large opening 6a of 10 the blade and entering the recesses 8 of the cap, whereby the guard and cap will be retained in shaving relation, and then the handle may be screwed on the stem 5 for clamping the members 1 and 2 against the blade. 15 Since the projections 7 and the recesses 8 of the guard and cap members locate and retain said members in shaving relation but do not themselves retain the blade 6 in shaving position, the latter will be retained in 20 said position by the projections 9 without regard to the projections 7, since without the projections 9 the blade 6, having the enlarged opening 6a, would be liable to be inaccurately located between the clamping members.

25 Having now described my invention, what I claim is:

30 1. A safety razor comprising blade clamping members, means to clamp said members

against a blade, one of said members having projections and the other recesses accurately fitting said projections and locating the two members in shaving relation, one of said members having an independent set of projections to locate and hold in shaving position a blade that has a large internal opening affording clearance with respect to said first-named projections.

35 2. A safety razor comprising a guard having projections and a cap having recesses accurately fitting said projections for locating the cap and guard in shaving relation, said cap having also an independent set of projections to locate and hold in shaving position a blade that has a large internal opening affording clearance for the projections of the guard.

40 3. A safety razor comprising a guard having projections, a cap having cap-locating recesses accurately fitted to said projections for locating the cap and guard in shaving relation, means to clamp the cap and guard against an interposed blade, and a blade having a large internal opening or openings leaving the projections of the guard free and clear within the periphery thereof and projections at the opposite ends of the blade, the cap having projections at its ends to co-operate with the projections of the blade for registering and holding the blade in shaving position between the cap and the guard.
